CLAIM

The ornamental design for a pipe fitting, as shown and described.

DESCRIPTION

FIG. 1 is a top perspective view of the pipe fitting according to the present invention;

FIG. 2 is a bottom perspective view of the pipe fitting of FIG. 1;

FIG. 3 is a front view of the pipe fitting of FIG. 1;

FIG. 4 is a right side view of the pipe fitting of FIG. 1, where the left side view (not shown) is a mirror of the right side view;

FIG. 5 is a top view of the pipe fitting of FIG. 1; and,

FIG. 6 is a bottom view of the pipe fitting of FIG. 1.
